UNITED STATES PATENT OFFICE.

WILHELM MAYBACH, OF CANNSTATT, GERMANY.

INTERNAL-COMBUSTION ENGINE.

1,092,930.

Specification of Letters Patent. Patented Apr. 14, 1914.

Application filed April 8, 1912. Serial No. 689,225.

To all whom it may concern:

Be it known that I, WILHELM MAYBACH, a subject of the King of Wurttemberg, and resident of 9 Freiligrathstrasse, Cannstatt, in the Kingdom of Wurttemberg, German Empire, have invented a certain new and useful Internal-Combustion Engine, of which the following is a specification.

This invention relates to oscillatory internal combustion engines and particularly to those having a four-stroke cycle, and the object of the present invention is to simplify the construction of such engines and of the valve mechanism therefor.

According to the present invention the closed end of the cylinder is carried by a secondary crank shaft so as to be caused to move over a curved path in conjunction with the oscillatory movement imparted to the cylinder from the main or driving crank shaft. The cylinder is provided with a single port formed in a flat disk-shaped valve face on the side of the cylinder, this valve face coöperating with a similar stationary valve face provided with inlet, exhaust and ignition ports adapted to successively register with the port in the cylinder.

The throw of the secondary crank shaft is preferably equal to or approximately equal to the compression space in the cylinder and the secondary crank shaft is adapted to be rotated in the opposite direction to the main crank shaft and at half the angular velocity thereof, so that when the piston is at the end of its in-stroke, the axis of the cylinder is in or approximately in the plane containing the axes of the crank shafts and its closed end either nearest the axis of the main crank shaft or in its most remote position therefrom, so that the scavenging of the cylinder during the exhaust stroke is perfectly attained.

In order that the invention may be more clearly understood, reference is made to the accompanying drawings, whereon the invention is illustrated by way of example as applied to a twin-cylinder motor.

Figure 1 is a diagrammatic view representing the valve movements, Fig. 2 is a vertical section through one of the engine cylinders, Fig. 3 is a vertical section at right angles to Fig. 2, and Fig. 4 is a transverse section on the line A—B of Fig. 3.

a and *a'* designate the two cylinders and *b* and *b'* their respective pistons, which terminate in bearings *i* on the crank pins *k* of

the crank shaft *c*. The cylinders *a* and *a'* terminate at their upper closed ends in bearings *e* rotatably mounted on the crank pins *f* of the secondary crank shaft *d*, while the lower ends of the cylinders *a* and *a'* terminate in a forked part *g*, which serves for guiding the downward extension *h* of the pistons *b* and *b'*. The cylinders *a* and *a'* each carry a flat valve face *l* provided with a port *m* opening into the cylinder and coöperating with the valve face *l* is a valve face *n* formed on the engine casing and provided with inlet ports *p*, exhaust ports *o* and ignition ports *q*.

r designates the ignition plugs and *s* guide-bars, which are adapted to maintain the valve faces *l* and *n* in contact with one another and at the same time permit the valve face *l* to slide over the valve face *n* during the oscillation of the engine cylinder.

Mounted on the main crank-shaft *c* is a gear wheel *t* gearing with the gear wheel *u* on the lower end of a vertical rotatable shaft *z*, carrying at its upper end a gear wheel *v* meshing with a gear wheel *w* on the secondary crank shaft *d*, the ratio of the gearing being such that the crank shaft *d* is driven at half the angular velocity of the main crank shaft *c* and in the opposite direction thereto.

Referring now to Fig. 1 of the drawings: The full line *x* indicates the curve described by the central point of the cylinder port *m* during one cycle of operations of the engine, the dotted circle *y* indicating the position of the cylinder port *m* when intermediate the exhaust port *o* and inlet port *p*. The dotted circle *y'* illustrates the position of the cylinder port *m* at the completion of the suction stroke, while the dotted circle *y*² designates the position of the cylinder port at the moment of ignition when in alignment with the ignition port *q*, it being assumed in this case that the dead points of the two crank shafts coincide. The numbers 1 to 16 inclusive on Fig. 1 of the drawings indicate the respective positions of the upper and lower crank pins and of the cylinder port respectively.

In Fig. 3 the cylinder *a* is shown at the moment of ignition while the cylinder *a'* is shown in the position assumed during the change from the exhaust stroke to the admission stroke.

It will be readily seen that if the crank shaft *c* is rotated in a clockwise direction, the secondary crank shaft *d* will be rotated

in the opposite direction, so that the cylinder port *m* will describe the lower part of the curve *z* during the lower part of its movement and during the upper part of the movement of the crank pin *k*, and that, when the cylinder is in the position corresponding to the cylinder *a'* of Fig. 3 the crank pin *f* of the secondary crank shaft *d* is in its lowermost position, and the piston in its highest position, thus insuring a complete scavenging action. On the further movement of the crank shafts the piston and cylinder commence the suction stroke and on their return movement the explosive charge drawn in from the port *p* is compressed and ignited when the piston is almost at the end of its inward stroke, when the cylinder port *m* registers with the ignition port *q*.

By rotating the secondary crank shaft in the opposite direction to, and at half the angular velocity of the main crank shaft, and by disposing the crank shafts so that their dead points coincide and so that, when the piston is at the end of its in-stroke, the axis of the cylinder is in or substantially in the plane containing the axes of the two crank shafts, not only is a complete scavenging effect achieved but, at the same time, the symmetric curve *z* described by the port *m* is such that separate inlet and exhaust ports can be provided and these most suitably arranged to fulfil the conditions of admission and exhaust.

It will of course be understood that if desired the crank shaft *d* may be arranged in advance of or lag behind the main crank shaft *c*. When the crank shaft *d* is in advance of the crank shaft *c*, the suction stroke will be somewhat increased, while the expansive stroke will be correspondingly decreased.

It will of course be understood that if desired the number of cylinders and the position of the cranks may be varied according to requirements and that, if desired, the ignition plugs *r* instead of being arranged in the engine casing, as illustrated in the drawings by way of example, may be mounted on the cylinder without departing from the scope of the appended claims.

I claim:

1. An internal combustion engine comprising an oscillatory cylinder closed at one end and having a single port, a piston movable in said cylinder, a main crank shaft to which said piston is connected, said cylinder being oscillated by said main crank shaft, a carrier arm on the closed end of said cylinder, a secondary crank shaft on which said carrier arm is oscillatorily mounted so as to cause said cylinder to oscillate about said secondary crank shaft, valve means having ports for controlling the admission and exhaust of an explosive charge to and from said cylinder, and ignition means for igniting

said charge in the cylinder, the port in said cylinder consecutively registering with the admission port of said valve means, with said ignition means and with the exhaust port of said valve means.

2. An internal combustion engine comprising an oscillatory cylinder closed at one end and having a single port, a piston movable in said cylinder, a main crank shaft to which said piston is connected, said cylinder being oscillatory about said main crank shaft, a carrier arm on the closed end of said cylinder, a secondary crank shaft on which said carrier arm is oscillatorily mounted so as to cause said cylinder to also oscillate about said secondary crank shaft, means for rotating said secondary crank shaft in the opposite direction to and at half the angular velocity of said main crank shaft, valve means having ports for controlling the admission and exhaust of an explosive charge to and from said cylinder, and ignition means for igniting said charge in the cylinder, the port in said cylinder consecutively registering with the admission port of said valve means, with said ignition means and with the exhaust port of said valve means.

3. An internal combustion engine comprising an oscillatory cylinder closed at one end and having a flat portion at one side with a port therein, a piston movable in said cylinder, a main crank shaft to which said piston is connected, said cylinder being oscillatory about said main crank shaft, a carrier arm on the closed end of said cylinder, a secondary crank shaft on which said carrier arm is oscillatorily mounted so as to cause said cylinder to also oscillate about said secondary crank shaft, and a stationary flat valve plate registering with the flat portion of said cylinder and having admission and exhaust ports therein adapted to successively register with the port in the flat portion of said cylinder.

4. An internal combustion engine comprising an oscillatory cylinder closed at one end and having a flat portion at one side with a port therein, a piston movable in said cylinder, a main crank shaft to which said piston is connected, said cylinder being oscillatory about said main crank shaft, a carrier arm on the closed end of said cylinder, a secondary crank shaft on which said carrier arm is oscillatorily mounted so as to cause said cylinder to also oscillate about said secondary crank shaft, a stationary flat valve plate registering with the flat portion of said cylinder and having admission and exhaust ports therein adapted to successively register with the port in the flat portion of said cylinder and ignition mechanism carried by said valve plate and also adapted to successively register with the port in the flat portion of said cylinder.

5. An internal combustion engine comprising an oscillatory cylinder closed at one end and having a single port, a piston movable in said cylinder, a main crank shaft to
5 which said piston is connected, said cylinder being oscillatory about said crank shaft, a carrier arm on the closed end of said cylinder, a secondary crank shaft on which said carrier arm is oscillatorily mounted so
10 as to cause said cylinder to also oscillate about said secondary crank shaft, valve means having ports for controlling the admission and exhaust of an explosive charge to and from said cylinder, and ignition
15 means for igniting said charge in the cylinder, the port in said cylinder consecutively registering with the admission port of said valve means, with said ignition means and with the exhaust port of said valve means, said secondary crank shaft being rotated 20 in the opposite direction to and at half the angular velocity of the main crank shaft and being so disposed, relatively to said main shaft, that, when the piston is at the end of its in-stroke, the axis of the cylinder 25 is substantially in the plane containing the axes of the two crank shafts.

In witness whereof I have hereunto set my hand in the presence of two witnesses.

WILHELM MAYBACH.
